(57) **CLAIM**

The ornamental design for a deer decoy, substantially as shown and described.

DESCRIPTION

FIG. 1 is a perspective view of one embodiment of the deer decoy of the present disclosure.

FIG. 2 is a perspective view of one embodiment of the deer decoy of the present disclosure illustrating an opening for receiving a device to facilitate movement of a tail portion.

FIG. 3 is a front view of one embodiment of the deer decoy of the present disclosure.

FIG. 4 is a perspective view of one embodiment of the deer decoy of the present disclosure.

FIG. 5 is a front view of one embodiment of the deer decoy of the present disclosure.

FIG. 6 is a front view of one embodiment of the deer decoy of the present disclosure further including a head portion; and, FIG. 7 is a perspective view of one embodiment of the deer decoy of the present disclosure further including a head portion.

The broken lines shown in all views are for illustrative purposes only and form no part of the claimed design.
